EQUIPMENT FOR COLLECTING WORKPIECES

Guido Bersa, Kapfenberg, Steiermark, Austria, assignor to Gebr. Bohler & Co. Aktiengesellschaft, Vienna, Austria

Application January 18, 1957, Serial No. 634,878

Claims priority, application Austria January 23, 1956

5 Claims. (Cl. 193—38)

This invention relates to equipment for collecting workpieces, more particularly for piling such workpieces with aligned ends in a receiver, which may consist of a trough, a cooling bed or the like. The workpieces to be collected are discharged by feeding means at a predetermined velocity in a predetermined direction and in a predetermined position. An upwardly facing, rigid slideway is provided, the longitudinal axis of which extends in said predetermined direction and which has an inclination transverse to said longitudinal axis. This slideway is arranged slidably to receive said workpieces directly from said feeding means in a zone which is spaced above the lower side edge of the slideway and adjacent to one end of the slideway. The slideway is adapted to progressively reduce the velocity of the workpieces in the predetermined direction on the slideway by friction and the inclination of the slideway is sufficient to cause each of said workpieces to move laterally from said slideway across a predetermined portion of the lower side edge thereof when the workpieces are allowed to move freely on the slideway. It is apparent that the movement of the workpieces on the slideway will be substantially in accordance with a parabolic curve. When the workpieces consist, for example, of bars discharged by the roller table in the axial direction of the bars, the latter will not change their position while on the slideway.

The slideway is preferably of sufficient length to reduce the velocity of the workpieces in said predetermined direction substantially to zero on said slideway. In this case the inclination of the slideway is preferably such as to cause each of said workpieces to reach the lower edge of the slideway when the velocity of the workpiece in said predetermined direction has been reduced substantially to zero. In this case the equipment will enable the piling up even of deformable, for example, hot bars beside the slideway without deformation of the bars.

To ensure that all workpieces are piled up with their ends exactly aligned it is essential, or at least desirable, that the factors which determine the movement of the workpiece on the slideway be maintained constant for all workpieces handled in a run. These factors include:

- (a) The direction in which the workpieces are moving when they are received by the slideway;
- (b) The velocity of the workpieces in said direction when they are received by the slideway;
- (c) The position of the workpiece at the time at which it is received by the slideway;
- (d) The weight of the workpiece;
- (e) The coefficient of friction between those portions of the workpiece which contact the slideway and the latter;
- (f) The size and shape of the surface portions of the workpiece which contact the slideway.

In this specification and the appended claims, the term "identical workpieces" has been used to describe workpieces which are identical with respect to the factors *a*, *e*, and *f* above.

The slideway may also be used as a cutting table for intermittent cutting operations. For this purpose the in-

2

clination of the slideway must be sufficient to enable the workpieces, which are temporarily held in position on the slideway during the cutting operation, to start moving down the slideway as soon as they are released. This inclination is usually greater than the optimum inclination of the slideway when used only for collecting operations.

Roller-tables have become known for an automatic collection of the workpieces. They have to be lifted on one side and to be furnished with rolls, which have to be turned into transversal direction.

Equipments for piling up tubes and bars have become known, furnished with a roller-gear-bed, along which the workpieces are gliding. As soon as they reach the end of that roller-gear-bed they are forced aside by lowering-edges and made to roll down to the pile along a slope. Another equipment for periodical ejection of the continuously arriving rolling-bars provided a pressure-medium, e.g. columns of air or water for ejection. In this equipment, however, the workpieces are not arranged flush with each other, so that additional devices are required, which can be dispensed if an equipment as described by the invention is used.

The invention will be explained hereinafter with reference to illustrative embodiments shown in the drawings, in which:

Figs. 1 and 2, respectively, are a side elevation and a top plan view showing collecting equipment according to the invention.

Figs. 3a and 3b are sectional views taken on lines A—B and C—D, respectively, of Fig. 1. Fig. 3b also shows a means for adjusting the slideway to the desired inclination.

Fig. 4 is a top plan view showing another embodiment of the invention,

Fig. 5a is a side elevation showing the collecting equipment of Fig. 4 viewed in the direction indicated at E in Fig. 4, and

Fig. 5b is a sectional view taken on line F—G of Fig. 4.

With reference to Figs. 1 to 3, rolled bars *a*, which have been cut to length, are discharged by the roller table *c*, exactly in the axial direction of the bars and at a predetermined velocity in said direction. The longitudinal axis of the upwardly facing, rigid slideway *b* extends in the axial direction of the bars *a*. This slideway *b* has an inclination transverse to its longitudinal direction and is arranged slidably to receive the bars *a* from the roller table *c* adjacent to the end of the slideway which is near the roller table in a zone which is spaced from the lower side edge of the slideway. In the position of the slideway indicated with solid lines in Fig. 3 this lower side edge is the side edge *d'* identified in Fig. 2. The slideway *b* is adapted progressively to reduce the velocity of the bars *a* in their axial direction and the inclination of the slideway is sufficient to cause the bars *a* to move laterally from the slideway across a predetermined portion of the lower side edge *d'* thereof when the bars *a* are allowed to move freely on the slideway.

A receiver, such as the trough *e'*, is arranged beside and below this predetermined portion of the lower side edge *d'* of the slideway *b* and receives the bars moving across this side edge.

For collecting deformable workpieces, e.g., hot bars *a*, the length of the slideway *b* is such that it reduces the velocity of the bars *a* in the axial direction thereof substantially to zero while the bars are on the slideway and the inclination of the slideway is such that when the bars are allowed to move freely on the slideway they will reach the lower edge *d'* of the slideway when their velocity in their axial direction has just been reduced substantially to zero. In this case the bars *a* will drop into the trough *e'* substantially without any velocity in their axial direc-

tion. If the hot bars *a* were still moving in their axial direction while dropping into the trough *e'*, they would be likely to strike against a wall of the trough *e'* or fall into the same with one end ahead of the other; in both cases the hot bars would be liable to be deformed.

As viewed in Fig. 3 the slideway *b* may be transversely inclined selectively toward the left or to the right. The latter position is indicated with dotted lines in Fig. 3. When the equipment is used for collecting bars *a* cut from successive ingots, all bars cut from one ingot may be collected, for example, in the trough *e'*. During the short period between the discharge of the last bar of this ingot and the first bar of the next ingot the slideway *b* can be tilted over to the other side to discharge all bars from this second ingot across the side edge *d*, which is now the lower side edge, into the trough *e* arranged opposite to the trough *e'*. In the meantime, the trough *e'* can be emptied.

Any suitable means may be utilized to adjust the slideway *b* to the desired inclination. An example of such means, which does not form part of the invention, is particularly shown in Fig. 3b. An arm *p* depends from the underside of the slideway member *b* and carries pins *q* which are received by the bearing eyes *s* of a push rod *t*, which is connected by a self-locking transmission *u* to a reversible electric motor *v*, the energization of which will cause the slideway member *b* to be adjusted to the desired inclination. The self-locking transmission *u* will hold the slideway member *b* in its adjusted position when the motor *v* is deenergized.

The point where the bars *a* move across the side edge *d* or *d'* of the slideway *b* can be varied and precisely adjusted by slight changes in the inclination of the slideway *b*. To enable this adjustment of its inclination, the slideway *b* is carried by a supporting structure, which comprises three semicircular members *f* rigid with the slideway *b* and disposed on the underside thereof. The underside of each of these members *f* is shaped in accordance with an arc of a circle extending in a vertical plane which is at right angles to the longitudinal axis of the slideway *b*. The underside of each of these members *f* is engaged by laterally spaced rollers *g*, the axes of which are parallel to the longitudinal axis of the slideway *b*. With the aid of an appropriate drive the transverse inclination of the slideway *b* can thus be adjusted throughout a range which includes an intermediate position in which the slideway *b* has no transverse inclination with respect to its longitudinal axis.

It is apparent from Figs. 4 and 5a and 5b that the equipment described may also be used as a cutting table. The slideway *b* is arranged slidably to receive the workpiece across that end of the slideway which is near the roller table *c*. For use of the slideway as a cutting table, an axial stop means consisting of an adjustable pivoted stop *i* (Fig. 5b) is moved into the path of the workpiece so as to be engageable by the latter to limit the movement thereof in its axial direction before the workpiece has been entirely received by the slideway *b*. In this case the workpiece may consist of a continuous ingot. Furthermore, a pivoted stop bar *h* is moved into the path of the workpiece to be engageable by the same to limit the movement of the workpiece in the direction of the inclination of the slideway *b* when the workpiece has engaged the stop *i*. When the workpiece has engaged the stops *h* and *i* it is cut off by the shears *l* between the roller table *c* and the slideway *b*. Then the stop bar *h* is lifted for a short time. In this case the slideway *b* is set to an inclination sufficient to cause the cut-off bar to move from standstill across the lower side edge of the slideway *b* and fall into the trough *k* disposed below and beside said side edge when the stop bar *h* has been lifted out of the path of the workpiece. The entire operation can be repeated after the stop bar *h* has been moved back into the path of the workpiece.

Any suitable means may be utilized to remove the stop bar *h* out of the path of the workpieces. An example of such means, which does not form part of the invention, is shown in Fig. 5b and comprises a reciprocable motor *r* connected by a linkage *x* to the stop bar *h* and operable to lift and lower the bar from and to the slideway *b*.

The equipment according to the invention requires only a small space and enables the piling of bars, billets and the like, which are supplied in rapid succession after they have been cut to equal lengths, e.g., with rotary shears moving with the bar, as well as the collecting of rolled bars which have been cut off on the slideway itself.

I claim:

1. Equipment for collecting workpieces, which comprises feeding means for discharging workpieces along a predetermined straight path, an upwardly facing, rigid slideway the longitudinal axis of which extends in the direction of said path and which is unmovable in the direction of said path and arranged to receive said workpieces adjacent to one end of said slideway to permit them to move on said slideway in the direction of said path with sliding friction, and a supporting structure carrying said slideway with freedom of pivotal movement about an axis which is parallel to said longitudinal axis to a position in which said slideway has an inclination transverse to said longitudinal axis to cause said workpieces to move laterally from said slideway when said workpieces are allowed to move freely on said slideway.

2. Equipment as set forth in claim 1, in which said feeding means are arranged to discharge substantially identical workpieces at a predetermined velocity along said path to said slideway and said slideway is of sufficient length to reduce the velocity of said workpieces in the direction of said path substantially to zero only by the sliding friction of said workpieces on said slideway when said workpieces are allowed to move freely on said slideway and the inclination of said slideway is such as to cause said workpieces to move laterally from said slideway after their velocity in the direction of said path has thus been reduced substantially to zero.

3. Equipment as set forth in claim 1, which comprises lateral stop means removably mounted in the path of said workpieces on said slideway when the same has said inclination, said lateral stop means being engageable by each of said workpieces to limit the lateral movement thereof on said slideway.

4. Equipment as set forth in claim 3, which comprises axial stop means removably mounted in the path of said workpieces and engageable by each of said workpieces to limit the movement thereof in the direction of said longitudinal axis of said slideway, and in which said lateral stop means is engageable by each of said workpieces to limit the movement thereof in the direction of said inclination when said workpiece has engaged said axial stop means.

5. Equipment as set forth in claim 4, in which said axial stop means is removably mounted in the path of said workpieces to be engageable by each of said workpieces to limit the movement thereof in the direction of said longitudinal axis of said slideway before the workpiece has been entirely received by said slideway, and which comprises cutting means disposed between said feeding means and said slideway adjacent to the path of said workpieces and operable to cut each of said workpieces when the same engages said axial and lateral stop means.
